PROPELLION MEANS

William Robert Mobley, Miami, Fla., assignor of
one-half to F. W. Bradby, Louisville, Ky.

Application March 12, 1931. Serial No. 522,043

7 Claims. (Cl. 170—135)

My invention relates to improvements in propulsion means for water-craft, air-craft and land vehicles,—comprehending also a novel method of effecting locomotion or propulsion of such vehicles.

Heretofore the propulsion of air-craft and water-craft has been effected largely by means of the conventional screw propeller. The propeller,—in effect,—screws its way through the fluid in which it operates and either pushes or pulls the vehicle along.

Such propellers cause the fluid in the immediate vicinity of the propeller to be set in motion in the direction opposite to that of the travel of the propeller and vehicle. This results in the consumption of a large amount of power without a proportionate useful result,—namely forward impulse of the craft.

The motion of the fluid set up,—namely the forcing of the same in the opposite direction to the rotation of the screw propeller and the direction of travel of the ship or craft prevents, in the case of air-craft, the control or landing of such craft at a low rate of speed. By the same token the ascension of the air-craft from the ground is difficult except when same is traveling at a high rate of speed and the propeller revolving at a high R. P. M.

The present invention is calculated to overcome the difficulties mentioned hereinabove and avoids the loss of power which results from the objectionable propelling of the fluid in the opposite direction to that of the travel of the craft,—and aims to provide in advance of the craft and propeller a vacuum which, with a high pressure area existing rearwardly of the craft or propeller, tends to force the propeller and craft forwardly.

A further object of the invention is to effect the forward propulsion of the craft by means of a novel propeller which will disturb but a minimum amount of fluid,—the propeller being designed so as to prevent the return of fluid once displaced from in advance of the propeller.

The invention also contemplates a propeller, which in the case of air-craft will greatly facilitate navigation and comfort in travel, since the objectionable rearward currents generated by the propeller, and commonly referred to as "back-lash", are eliminated entirely so as to reduce very materially the element of "rough air" in air-craft navigation.

A further object of the invention is to provide a novel propulsion means, for the purpose stated which comprehends a driven propeller, with a shield member in rear thereof providing a plane, or chamber-defining surface,—exposed to the propeller, and the blade or blades of the propeller being substantially plane and lying in planes substantially parallel with the axis of the propeller, whereby when the propeller is in opera-

tion, to create by centrifugal action, a vacuum at said surface and in advance thereof, without rearward driving of the adjacent fluid, although the area in rear of said surface will be a high pressure area as compared to the vacuum area in advance of said surface which cooperates with the vacuum for effecting forward movement of the propeller and body on which it is mounted.

A further object of the invention resides in the provision of a novel propeller which utilizes the entire area in front which is defined by the circumferential path of the blades, for the creation of a vacuum, the cross section of which will, at least, equal the diameter of the circular path defined by said blades, whereby a much smaller propeller may be used than would otherwise be necessary to lift or advance a given weight,—the nature of the propeller and its mode of operation being such that no power will be lost or expended in driving air or fluid continuously against a built up pressure in the rear.

Another object of the invention is to provide a propeller which is simple in construction, economical to manufacture, the unit comprising the propeller being of such a nature as to eliminate parts likely to be broken and get out of order.

The invention also resides in certain novel features of construction, combination and arrangement of the various parts and in methods of use and modes of operation, all of which will be readily apparent to those skilled in the art upon reference to the accompanying drawing in connection with the detailed description appearing hereinafter.

It is to be understood that I have disclosed in the drawing what now appear to be preferred forms of the invention. However, it is clear that same are susceptible of considerable change and modification within the spirit and scope of the subject matter claimed hereinafter.

In the drawing, wherein the same reference characters have been used to designate the same parts in all views,

Figure 1 is a side elevational view illustrating one form of the invention;

Figure 2 is a front elevational view of the device of Figure 1;

Figure 3 is a sectional view, taken on the line 3—3 of Figure 2;

Figure 4 is a side elevational view of another form of invention, wherein a disk is substituted for the chambered member of Figures 1, 2 and 3;

Figure 5 is a fragmentary view, partly broken and partly in section,—disclosing a further form of the invention wherein a chambered member and propeller turn together on the same center, and

Figure 6 is a fragmentary perspective view of the form of invention shown in Figure 5.

Referring specifically to the drawing, and par-

ticularly to Figure 1, it will be noted that I have disclosed for purposes of illustration a base-like member 2, providing the spaced bearings and supports 3 for the pintles 4 of a semi-spherical chambered member 5. It is evident that the member 5 is supported for pivotal movement about the horizontal axis at 4, whereby the direction of propulsion may be changed by turning the propeller and with it the member or shield 5 on the axis 4, more or less, relative to the sub-structure, a part of which latter is shown at 2 and 3.

In carrying out the invention the semi-spherical member 5 is provided with a bearing 6, in which is journalled a shaft 7 extending through the bearing, and which may be driven by any suitable source such as a motor, not shown.

The forward end of the shaft 7 is provided with a number of blades 8, of which four are shown in the present instance. These blades, when viewed in plan, are shown to be substantially segmental in shape with their curved edges outwardly so as to provide, in effect, a continuation of the spherical member 5.

Assuming the device of Figure 1 to be at rest, and ready to be started, there will be obviously a quantity of air or other fluid in the spherical recess of the member 5.

However, upon starting of the shaft 7 and the propeller carried thereby, it will be obvious that the blades will set up strong centrifugally acting currents in the area about the propeller blades 8. These centrifugally acting air currents and the action of the rotating propeller which create them, will obviously exhaust air from the exposed, or open, front of the semi-spherical member 5. Thus, a vacuum will be created in said member 5, and in the area in front of the blades 8. Atmospheric pressure in back of the member 5 will naturally tend to force the member 5 forwardly due to the vacuum created within it, and to its front.

Assuming the unit of Figure 1 to be mounted on an air-craft, it will be readily seen that the action set up will result in the craft being sucked through the air as a result of the vacuum created in the chamber of member 5.

In actual tests made with a small model involving this principle, tremendous power has been generated. Obviously the device will generate more power than will a fan-type propeller which depends very largely upon the throwing of the fluid rearwardly to advance the ship or body which carries the propeller.

It will be perfectly plain that the throwing of the fluid rearwardly by the screw-type propeller necessarily must overcome the resistance of the air or fluid into which the fluid adjacent the propeller is thrown.

Obviously, also the screw-type propeller will produce a tremendous "back-lash" or "eddying" current which results in the air-craft "riding rough" in its travel, particularly where natural air currents are traveling in a direction contra to the synthetic air currents set up by the screw propeller.

The provision of a plurality of blending helical or arcuate air currents about the periphery of the blades 8 in my propeller, as shown in Figure 1, creates a channel or vacuum through which the air-craft or ship will be pulled and the surrounding swerving air currents will tend to stabilize the ship and counteract the effect of any natural air currents that may be existent at a particular time.

The matter of the air currents set up by my

propeller comprising the blades 8 is shown diagrammatically in Figure 1.

Figure 5 illustrates a further form of the invention which comprehends a base 10 providing bearing arms 11, in which is journalled a shaft 12 to which is keyed a semi-spherical casing 14 similar to the semi-spherical casing 5 of Figure 1. In Figure 5 the shaft 12 also carries keyed thereto a fan 13 of the same type shown in Figure 1.

It will be obvious that the difference between the construction shown in the last described form of the invention (Figure 5) and that of Figure 1 is that in Figure 1 the semi-spherical casing is stationary and does not revolve.

In further carrying out the invention, I have availed of a further modification, which is shown in Figure 4 and which comprehends a base 20 providing bearing arms 21 in which are journalled the stub ends or shafts 22 at diametrically opposite peripheral portions of a disk 23. The disk itself is provided with a bearing 24 for a shaft 25 which carries at its outer end the blades 26, which are in all respects similar to the blades shown in the previously described figures.

It will be obvious that the form of the invention, shown in the last embodiment comprising the disk 23, differs from the form of invention shown in Figure 1 only in the absence of the spherical member 5,—the disk in the last form of the invention being substituted for the spherical member 5.

However, the device of Figure 4 functions the same way, in that a vacuum will be created in front of the disk 23 leaving a high pressure area in rear thereof. The high pressure area in rear, and the vacuum in front, produce a sucking of the propeller and craft through the air.

It is to be observed that while I have illustrated the invention to disclose a plane surface in rear of the propeller blades, or a semi-spherical chamber,—yet any recess or chamber of whatever configuration in rear of the rotating fan would serve the same purpose and the functioning of the device would be identical.

Having thus described my invention, what I claim as new and desire to secure by Letters Pat- ent is:

1. A propulsion means which is adapted for propelling a body through a fluid and which comprises a member providing front and rear surfaces, a rotor rotary relative to said member and operating adjacent said front surface and having blades disposed radially of the axis of said member with their edges and sides in places perpendicular to said surface, and driving means for said propeller, and a pivotal mounting for said parts the axis of which mounting is cross-wise to the axis of the rotor.

2. The combination set forth in claim 1, and said front surface of said member being concave and providing a chamber adjacent said blades.

3. The combination set forth in claim 1, and said front surface being concave and providing a chamber closed at its rear whose cross section is substantially equal to the diameter of the rotor in advance thereof.

4. A propulsion means having a rotor and a concave member arranged close to the rear of the rotor, and fixed relative to the turning of the rotor, to obstruct rearward flow of air, and acting to promote radial flow of air and the forming of a partial vacuum in front of said member while its rear face is subjected to atmospheric pressure.

5. In a propeller the combination of a power shaft having a bearing, a pivot arranged trans-

versely to said bearing on which pivot the shaft is adjustable to different angles, propeller blades on said shaft, and a shield arranged at the rear of said blades, said shield being independent of 5 said blades and attached to said bearing and adjustable with the bearing, and said power shaft being rotatable relative to said shield.

6. A propulsion means having a rotor and a shield member arranged close to the rear of the 10 rotor to obstruct rearward flow of air, and acting to promote radial flow of air and the forming of a partial vacuum in front of said shield while its face away from the rotor is subjected to atmospheric pressure, the shield member having 15 a transverse pivot whereon it is adjustable with the rotor to different angles.

7. A propulsion means for air craft and the like which comprises a member providing a surface extending across the axis of the propulsion means, a rotor having a blade lying in and having its sides lying in a plane substantially parallel with its axis and substantially perpendicular to said surface, said rotor being rotary relative to said member and adjacent said surface, mounting means including a transverse pivot for said rotor and member, and means for driving said rotor whereby its blades create a vacuum at said surface and in advance of said rotor and produce in addition centrifugal currents about the periphery of said rotor, whereby said rotor and said member may be turned to different angles.
